UNITED STATES PATENT OFFICE.

ARTHUR W. McCALLISTER, OF SHIDLER, OKLAHOMA, ASSIGNOR OF ONE-HALF TO
ALEXANDER R. O'BRIEN, OF BARTLESVILLE, OKLAHOMA.

CLAMP.

Application filed February 9, 1925. Serial No. 7,978.

To all whom it may concern:

Be it known that I, ARTHUR W. McCALLISTER, a citizen of the United States, residing at Shidler, in the county of Osage and State of Oklahoma, have invented certain new and useful Improvements in Clamps, of which the following is a specification.

This invention relates to improvements in clamps particularly well adapted to be used in connection with the pumping equipment of oil wells and the like.

The primary object of this invention is the provision of a clamp which may be readily and quickly detached, without the necessity of bolt adjustments; the improved clamp being preferably adapted to be used in connection with the pull or surface rods between the power application and pumping jacks of oil well pumping equipment.

A further object of this invention is the provision of a clamp adapted to be used in connection with oil well pumping equipment, embodying novel means for connecting a clevis to a pull or surface rod, in detachable manner, without means of bolts.

The conventional clamp used in connection with the coupling of the surface rod to the pumping jack and power mechanism of oil well pumping equipment, embodies the use of a plurality of bolts, which are extremely difficult to manipulate for removal of the clamp or clevis. Frequently the conventional clamp will break because the same has not been properly tightened, and the occasions are of common occurrence where such breaks result in considerable loss, due to waste of oil; expenditure of labor; and maintenance expenses in connection with the destruction of the clamp. The improved clamp of this invention does away with the tedious process of bolting the clamp body to the surface rod and clevis, and embodies a novel means for quickly detaching the clevis with respect to the clamp body; and a novel arrangement for the secure and quick attachment and detachment of the pull or surface rod with respect to the clamp body.

Other objects and advantages of this invention will be apparent during the course of the following detailed description.

In the accompanying drawings, forming a part of this specification, and wherein similar reference characters designate cor-

responding parts throughout the several views,

Figure 1 is a side elevation of the improved clamp, showing the same assembled and attached to an end of the surface rod.

Figure 2 is a cross sectional view taken through the clamp body, with the details assembled as is illustrated in Figure 1.

Figures 3 and 4 are cross sectional views taken substantially on their respective lines in Figure 2 of the drawing.

Figure 5 is a fragmentary sectional view taken through the improved clamp, particularly at the body thereof, showing the means by which the clamp may be connected to one type of surface rod of construction other than the construction of the surface rod illustrated in Figures 1 and 2.

In the drawing, wherein for the purpose of illustration is shown a preferred and modified form of the invention, the letter A may generally designate a surface or pull rod, or any other analogous element to which it is desired to attach the improved clamp B.

The improved clamp or coupling B preferably includes a body C; clevis D, detachable with the body C; and grip means E for detachable connection of the rod or element A with the body C.

First referring to the surface rod A, the same is of the type which is connected at one end to the pumping jack, and at the opposite end to the power line or mechanism. At each end thereof an improved clamp B is placed. The rods A are of numerous types, but in the drawing the same is of the type having the enlarged end or head portion 10^a at the ends thereof, which the clamp receives therein. Other types of rods, such as the rod K illustrated in Figure 5 are also conventionally used, and these are of uniform diameter from end to end, without the headed ends or enlargements, and in connection with such types of rod, a special type of grip mechanism L is used.

The clevis or U-shaped connecting link D is of somewhat novel formation, including the relatively straight leg portions 10 and 11, connected in a converging relation by the U-shaped bight portion 12; said legs 10 and 11 converging from the bight portion 12 towards their free ends, and at which free ends the legs 10 and 11 respectively provide the enlarged heads 13 and 14, which are

cylindrical in shape, and preferably provide circular shoulders 15 at the junctures of the same with their respective legs 10 and 11. The legs 10 and 11, as well as the eight portion 12 of each bolt or clevis D are circular in cross section.

The body C of the improved clamp or coupling device B is of novel formation, cast or otherwise fabricated in one piece, of durable material and construction. Inwardly of the opposite sides thereof, grooves 20 and 21 are provided, which extend in converging relation from one flat end surface 22 of the body C toward the opposite or outer side end surface 23 of the body C. These grooves 20 and 21 terminate in enlargements or sockets 25 and 26 respectively, at their ends adjacent the front surface 23 of the body, and these sockets 25 and 26 extend through said front surface 23, and at the juncture of said sockets with the grooves 20 and 21 abutment shoulders 28 are provided, against which the shoulders 15 of the U-shaped clevis member D abuts, as will be subsequently mentioned. It is to be particularly noted that the grooves 20 and 21 are of a diameter or width equal to the diameter of the legs 10 and 11 of the clevis D, to facilitate the insertion or extraction of the same, and these grooves extend from end surface to end surface of the body C, and through the sockets 25 and 26, although the width of said grooves 20 and 21 is less than the diameter of the sockets 25 and 26, as is illustrated in Figure 3 of the drawing.

As to the assemblage of the clevis D in the body C, the width of the body C from one grooved side to the other grooved side is just sufficient that the said body C may be tipped into the opening 30 at the enlarged end of the clevis D, as is illustrated by the dotted lines in Figure 1, when one leg of the clevis is in one groove at a side of the clevis receiving body C, so that from this dotted position the body C may be slipped downwardly toward the converging ends of the clevis D. With such an arrangement the legs 10 and 11 are received in the grooves 20 and 21, and as the grooves converge in the same relation as do the legs 10 and 11, the body C has a limited movement, so that the body C will engage in abutment against the legs 10 and 11 to lock the body C and clevis D together. In such position the enlargements 13 and 14 fit in the sockets 25 and 26 respectively, as is illustrated in Figures 1, 2 and 5 of the drawing, and the shoulders 15 abut the shoulders 28 to stably connect the clevis D and the body C. A slight wedging action tending to expand the legs 10 and 11 insures sufficient friction to clamp the clevis D and the body C against liability of accidental detachment until the body C and clevis D have a force applied thereto tending to disconnect the same by

moving them into the position illustrated by the clevis and the dotted lines of the body in Figure 1 of the drawing.

Referring to the grip device E by which the type of rod A is connected in the body C, it is to be noted that in connection with either the grip device E, or the grip device L, a uniformly tapering opening 35 is provided, which opens at the inside and the outside surfaces 22 and 23 of the body C, the tapered opening 35 tapering with a diminishing diameter from the inside surface 22 towards its outlet at the opposite surface 23.

The grip device E is preferably of two-part construction, including the segmental parts 40 and 41, although the same may be of a greater number of parts if desired. These segmental parts 40 and 41 when assembled about the end of the rod A are tapered, to fit into the tapered opening 35. The parts 40 and 41 when assembled provide an enlarged opening 44 at the inside or large end of the grip device E, for receiving the head or enlarged end 10a of the surface rod A. As the large tapered end of the grip device E fits in the large end of the tapered opening 35, it can readily be seen that any tendency of the rod A to pull away from the clamp B will cause the tapered sections 40 and 41 to wedge more firmly in the tapered opening 35, preventing any liability of disconnection of the rod A from the clamp B.

The grip device L preferably is also of two-part construction, including parts 50 and 51, which are segmental in formation, providing when assembled an external tapered surface and an internal passageway 52 adapted to receive the straight end of the rod K. The sections 50 and 51 when assembled provide a conical or tapered appearance, adapted to fit in the tapered opening 35 of the clamp body C. A novel feature of the grip sections 50 and 51 is the fact that the same are provided with a corrugated or internally grooved passageway 52; the corrugations or transverse grooves 56 being sharpened, or in the form of screw threads, so that the same will bite into engagement with the end of the rod K when the grip device L is seated in the tapered opening 35, and prevents any tendency to pull the rod K and clamp B apart.

From the foregoing description of this invention it is apparent that a novel type of clamp has been provided, which while the same may be generally used for a variety of purposes, it is especially adapted to be used in connection with the huge couplings or clamps, which are used in connection with the attachment of surface or pull rods to power line equipment and pumping jacks. The type of clamp is especially well adapted for such use, and may be easily and quickly attached and detached with respect to the

rod, and the body thereof may be easily and quickly attached or detached with respect to the clevis portions, in the manner above described. By actual tests, it has been found 5 that fifteen minutes is the minimum time which an operator can attach or detach the conventional bolt clamp with respect to the surface rod. With the novel clamp herein described, however, it has been found by actual test that one-half of a minute is only required to assemble the clamp upon a surface rod, and one-quarter of a minute is only required to disassemble the same with respect to the surface rod. The saving of such 10 15 a great amount of time is of considerable importance when weight is given to the inconveniences and delays which are thereby avoided in connection with the special application of the clamp to oil well pumping 20 equipment.

Various changes in the shape, size, and arrangement of parts may be made to the form of invention herein shown and described, without departing from the spirit of 25 the invention or the scope of the claims.

I claim:

1. A clamp comprising a body, jaw clamping means associated with the body, said body at the opposite outer edges thereof having 30 grooves therein opening outwardly along said sides in a convergent relation, and a clevis including side legs having portions thereof convergently disposed for detachable connection in the convergent 35 grooves of said body.

2. As an article of manufacture a clevis which is substantially U-shaped in formation including a pair of substantially straight leg portions connected by an articulate bight portion integral therewith, whereby 40 said leg portions are connected in a converging relation towards their free ends, and heads integrally formed at the free ends of said straight leg portions, providing abrupt shoulders at the juncture of the same 45 with said leg portions.

3. As an article of manufacture a clamp body providing a pair of convergent grooves opening at the opposite sides thereof and 50 opening at the ends thereof, said body having enlarged sockets extending inwardly of one end surface thereof at an end of each of said grooves.

4. As an article of manufacture a clamp body providing a pair of convergent grooves opening at the opposite sides thereof, and extending from end to end surface thereof, said grooves at their convergent ends having 55 enlarged sockets opening at the end surface of said body.

5. As an article of manufacture a clamp body providing a pair of convergent grooves opening at the opposite sides thereof, and extending from end to end surface thereof, said grooves at their convergent ends hav- 60

ing enlarged sockets opening at the end surface of said body, said body being provided with a tapered opening therethrough between said grooves and extending from end surface to end surface thereof, with the 70 larger diameter of the tapered opening occurring at the end surface of the body where the grooves are in farthest spaced relation.

6. A clamp of the class described comprising a body having grooves opening outwardly at opposite sides thereof with enlarged sockets at the ends of each of said grooves, and a clevis including legs adapted to fit into said grooves and including enlarged portions adapted to fit in said sockets 75 whereby to prevent movement of the body and clevis in one direction when so assembled.

7. A clamp comprising a body having convergent grooves formed inwardly at opposite sides thereof opening at an end surface of said body, and a clevis of U-shaped formation including legs converging towards their free ends, said body adapted to be assembled to the clevis with the clevis legs 80 at their convergent ends extending into the convergent grooves of the body to connect the body and clevis against movement away from each other in one direction.

8. A clamp comprising a body providing grooves at the opposite sides thereof opening at said sides and provided with enlarged sockets in the ends thereof opening at an end of said body, and a clevis of U-shaped formation including legs adapted to extend 90 into said grooves and provided with enlargements at the free ends of said legs for extending into said sockets for detachable connection of the body and clevis.

9. A clamp of the class described comprising a body provided with ways extending inwardly at opposite sides thereof, said ways extending along said body from end surface to end surface, said body being provided with enlarged sockets inwardly of one end surface at an end of each of said ways, said ways and sockets being disposed in convergent relation from one end of said body towards the opposite end wherein are disposed the said sockets, and a substantially U-shaped clevis including a pair of leg portions connected in rigid converging relation by means of a bight portion, said leg portions at their convergent ends having enlarged 100 portions thereon, said body being of a width permitting the assemblage of the same between said legs adjacent said bight portion of the clevis with one leg in one of its grooves whereby the other leg and other groove may be aligned to permit slipping of the body towards the convergent ends of said legs whereby to position the convergent legs in said convergent ways until the enlarged ends of said legs seat in the sockets 110 of said body whereby to securely and stably

120 125 130

- support the body and clevis in a detachable relation.
10. In a clamp of the class described the combination of a body provided with a 5 tapered opening therethrough, a wedge-shaped gripping device formed of a plurality of sections providing an enlarged socket in the enlarged end thereof, and a rod providing an enlarged portion for seating in 10 said socket whereby to wedge the sections of said grip against said rod to connect the same to said body.
11. In a clamp of the class described the combination of a body provided with a 15 tapered opening therethrough, a straight rod, and a substantially conical shaped sectional grip device providing an external tapered surface adapted to seat against the 20 tapered opening through the body, said sectional grip device providing a passageway therethrough having a plurality of circumferential grooves adapted to grip the said rod upon wedging of the grip device in said 25 tapered opening of the body to prevent detachment of the rod when an attempt is made to move the same away from said body.
12. A clamp of the class described comprising a body having a tapered opening 30 therethrough between the sides thereof extending from one end surface to the opposite end surface thereof, said body having ways grooved inwardly of the opposite sides thereof at opposite sides of the tapered opening and extending in a converging relation from the end surface whereon outlets the 35 enlarged end of said tapered opening towards the opposite end surface, a clevis pro-
- viding a pair of legs converging towards their free ends adapted to seat into the side 40 grooves of said body to prevent movement of the clevis away from the body when moved in one direction, a rod, and a conical sectional grip device adapted to seat in the tapered opening of said body and to wedge 45 in clamping engagement against said rod when an attempt is made to pull the rod away from said body.
13. In a clamp of the class described the combination of a body, a U-shaped clevis 50 including legs having enlargements thereon, said body having sockets thereon adapted to receive the leg enlargements therein to prevent movement of the clamp body in one direction away from said clevis, said body 55 having a way extending therethrough, a rod, and a wedge device adapted to seat in said way for clamping the rod to the body upon attempted movement of the rod away from said body in one direction.
14. In a clamp of the class described the combination of a body providing ways extending inwardly at opposite sides thereof and in a converging relation, a clevis provided with converging legs adapted to seat 60 in the ways of said body to prevent movement of the body from the clevis when a pull is exerted tending to move the same away from each other, a rod, said body having a way therethrough for receiving said rod, 70 and a wedge device disposed in said way for engaging said rod in a clamping relation to prevent disconnection of the rod and body when the same are pulled away from each other in one direction.

ARTHUR W. McCALLISTER.
